FOOD DISPENSER

Frank E. Wolcott, West Hartford, Conn.

Application December 13, 1938, Serial No. 245,460

5 Claims. (Cl. 221—76)

My invention relates to food dispensers. It has among its objects to provide an improved dispenser for comestibles or the like having improved and simplified resilient means for effecting flow therefrom. A further object is to provide improved quick detachable and connectible connecting means for said flow controlling means interlocked therewith. A still further object of my invention is to provide such improved flow controlling means and connecting means therefor included in an improved quick detachable and connectible closure construction. Other objects of my invention are to provide an improved quick detachable and connectible cap member cooperating in an improved manner with an improved combined sealing and actuating disc, and to provide such an improved construction whereby it is made possible to obtain the above results while producing an exceedingly simple, convenient, readily cleansed, and attractive construction, and one which is also adapted to be readily and inexpensively manufactured. These and other objects and advantages of my improved construction will, however, hereinafter more fully appear.

In the accompanying drawing, I have shown for purposes of illustration two embodiments which my invention may assume in practice.

In the drawing:

Figure 1 is a side elevation of a dispenser constructed in accordance with my improvements, the same being shown in its container in the position occupied when not in use;

Fig. 2 is a vertical sectional view on line 2—2 of Figure 1;

Fig. 3 is a top plan view of the construction shown in Figure 1;

Fig. 4 is a perspective view partially in section, of the dispenser removed from its support, with the cap and the flexible sealing and actuating disc shown in spaced relation to each other and in section above the dispenser to facilitate illustration;

Fig. 5 is a perspective view of the resilient sealing and actuating disc, and

Fig. 6 is a sectional perspective view of a modified form of the sealing and actuating disc.

Referring first to the construction shown in Figures 1 to 4, it will be noted that my improved dispenser, generally indicated at 1, is seated, when not in use, in the open top of an upstanding container 2, while being removable therefrom whenever desired for use; this dispenser herein having an improved closure and actuating structure, hereinafter described.

Referring more particularly to the dispenser 1, it will be noted that the same is herein in the form of a transparent glass container having a shoulder 3 substantially midway between its ends adapted to project above the upper edge 4 of the container 2, while the lower end of the dispenser, provided with a bottom outlet 5, is received vertically within the container 2; the upper end of the dispenser projecting above the container 2 and being provided with a roughened or corrugated portion 6 in such manner as to permit the dispenser to be readily grasped for use whenever desired. Further, it will be noted that improved combined closure and flow controlling means are provided on the upper end extremity of the dispenser 1.

In this improved construction on the upper end of the dispenser, it will be noted that the latter is provided with a shoulder 7 near its upper end, and a coarse threaded portion 8 above this shoulder, this threaded portion herein comprising a single thread and surrounding an open neck 9 of slightly less than the full diameter of the corrugated portion 6 and through which the dispenser 1 is adapted to be filled. Upon the upper edge of this neck 9, an improved resilient combined sealing and actuating member 10, herein in a disc of rubber, is provided. As shown, the upper edge of the neck 9 is flat, and the disc 10 is provided with a peripheral bottom edge or flange surface 11 engaging with the flat edge of the neck 9 and surrounding the open bottom of an axial, resilient, and normally raised but shallow dome portion 12 forming the body of the disc 10. This portion 12 also has a central upwardly projecting portion 13 thereon adapted to be engaged and depressed by a finger, and herein is also provided with a small axial air passage 14 leading through this portion 13 to the interior 15 of the dispenser 1. As shown, the disc 10 is also provided with an upstanding annular flange 16 around its periphery, herein projecting upward directly above the seal provided by the engagement of the portion 11 with the top edge of the neck 9 and of slightly smaller cross section than the portion 11. Moreover, it will be observed that an annular connecting cap member 17 is provided which has a threaded portion engageable with the threaded portion 8 on the neck 9, a preferably roughened grasping portion 18, and a lower flange 19; these portions of the cap being adapted to be disposed around the reduced neck 9 in such manner that with the cap threaded on the portion 8, the upper end of the dispenser is of substantially the diameter

of the corrugated portion 6 thereon. Moreover, it will be observed that the cap 17 is provided with a portion extending laterally above the flange 16 and provided with a somewhat wider annular groove 20 adapted to interlock this flange, while a further inwardly extending upwardly curved abutment portion 21 of annular form overlies and protects the portion of the resilient dome-like portion 12 inside the upstanding flange 16 on the disc 10, while being spaced from the central projection 13 in such manner as to allow free downward movement of the portion 12 and provide an abutment for an upper face thereof conforming to the curvature of the latter and limiting upward movement thereof.

Thus, it will be observed that when the cap 17 is threaded on the threads 8 on the neck 9, the resilient sealing flanges 11 and 16 on the disc 10 will be compressed by the cooperating groove 20 of the cap 17 in such manner as not only effectually to prevent too great downward movement or release of the disc, but also to form an effective seal around the top of the dispenser. It will also be observed that the portion 21 on the cap 17 cooperates to provide a protecting and limiting means for the adjacent resilient dome portion 12 of the disc 10, while permitting the projection 13 on that member to be readily depressed as desired. Further, it will be evident that the construction is such that downward pressure of a finger on the projection 13, the finger then being over the port 14 therein, will cause the dome to collapse and thereby cause pressure to be exerted on the top of any material in the dispenser 15 in such manner as to effect discharge through the bottom outlet 5. Moreover, the inherent resiliency in the disc 10, here formed of rubber, is such as to cause the dome 12 thereof to be returned automatically when the finger is removed, to the normal position shown in Figure 2, wherein the periphery of the portion 12 engages the inner surface of the portion 21 and is thus limited in its upward movement and protected by the latter portion.

As a result of my improvements, the construction, while being very effective in operation, is also markedly simple in use and in manufacture. Thus, it permits quick and ready removal or connection of the cover, as necessary, incident to filling or cleansing without requiring time-consuming and troublesome fitting on or taking off of an expansible cover. More particularly, it is necessary only to rotate the cap through a small number of degrees in order to permit the same to be lifted off and simultaneously release the sealing and actuating disc 10, which, due to its upstanding flange 16 and the threads on the cap, is retained in the latter and removable therewith. It will also be noted that the construction is sanitary, the disc 10 being readily separated from the cap whenever desired by simply pushing in on the projection 13. The construction further makes it possible to substitute a new actuator when desired, with facility and with a minimum of expense. Moreover, note that the structure of the disc 10 is such as to enable the latter to be of simple and rugged construction and to have long life in service. My improved structure also enables the cap member 17 to be formed of a small quantity of suitable material, as for example, any suitable molded and colored material, in such manner as to produce an inexpensive and attractive construction, while this cap member, not being subject to deterioration, is adapted to long life in service. Attention is

further directed to the fact that in my improved construction it is possible for the dispenser 1 to be filled while supported in the upstanding container 2, the cap 17 and disc 10 being so readily separable from and connectible to the dispenser as to make this possible, and any suitable closure means (not shown) for the bottom outlet 5 being provided in the bottom of the member 2.

In Figure 6, I have shown a modified form 10 of disc 10, wherein, instead of the port 14, there is no opening through the disc; this being a form which may be used with other types of liquids. The construction otherwise being the same as heretofore described, it enables certain of the 15 advantages thereof to be obtained, while, through the vacuum created as the dome 12 springs upward following release, this construction also makes it possible to suck back any liquid protruding from the outlet 5 when the finger is removed from the projection 13.

While I have in this application specifically described certain forms which my invention may assume in practice, it will be understood that these are shown for purposes of illustration, and that the invention may be modified and embodied in other forms without departing from its spirit or the scope of the appended claims.

What I claim as new and desire to secure by Letters Patent is:

1. In a dispenser, a container having an outlet and an apertured filling portion at opposite ends, a flow controlling resilient disc closing said portion, and an axially apertured enclosing cap clamping said disc on said container, said disc having a resilient dome portion and said cap having an annular portion normally engaging said dome portion.

2. In an actuating mechanism for a dispenser, a cap having internally threaded means thereon, a portion overlying the top of said threaded means and having an annular groove therein, and a resilient actuating member having a dome operable through said cap, a bottom peripheral sealing portion and an upstanding peripheral flange receivable in said groove, said cap having an axial aperture in its top and abutment means for said dome surrounding said aperture and between the same and said annular groove.

3. A cap for dispensers comprising an annular member having threaded means on its inner periphery and an axial aperture in its top, a downwardly opening annular groove around the top of said threaded means, and domed overlying abutment means surrounding and extending from said annular groove and having said aperture therein.

4. In an actuating mechanism for a dispenser, a cap having internally threaded means thereon, a portion overlying the top of said threaded means, a resilient actuating member having a dome in engagement with said overlying portion and a projection on said dome operable through an aperture in said cap.

5. In an actuating mechanism for a dispenser, a cap having internally threaded means thereon, a portion overlying the top of said threaded means and having an annular groove therein, a resilient actuating member having an upstanding peripheral flange receivable in said groove and a domed portion operable through an aperture in said cap, and an inwardly extending flange in said cap in abutment with said domed portion.
